FREDERICK E. CALSON, OF NEW BRITAIN, CONNECTICUT, ASSIGNOR TO LANDERS, FRARY & CLARK, OF NEW BRITAIN, CONNECTICUT, A CORPORATION OF CONNECTICUT

ELECTRIC SWITCH

Application filed March 29, 1929. Serial No. 350,862.

This invention relates to electric switches and more particularly to that type known as snap switches.

These switches are commonly used with 5 relatively large current, for example, in controlling circuits for toasters, stoves and other household appliances.

It is an object of the invention to provide 10 a snap switch in which the movable switch member or contactor has a shifting or varying pivot, resulting in speedy, accelerated movement into and out of circuit closing position with consequent reduction of arcs and longer life of the switch in service.

15 It is a further object to produce a pivot for imparting an eccentric movement to the contactor to ease the tension and reduce the strains on the spring.

With these general objects in view, the invention 20 consists in the features, combinations, details of construction, and arrangements of parts which will first be described in connection with the accompanying drawings and then more particularly pointed out.

25 In the drawings:—

Figure 1 is a plan view, with parts broken away and in section, of a switch constructed in accordance with the invention;

Figure 2 is a similar view of a modified 30 construction;

Figure 3 is a sectional view taken as on the line 3—3 of Figure 2;

Figure 4 is a detail plan and sectional view 35 of part of the actuator of the switch shown in Figure 2;

Figure 5 is a perspective view of the contactor of the switch;

Figures 6, 7, and 8 are diagrammatic views 40 (enlarged) showing the contactor in different position occupied during movement.

The construction illustrated as an example 45 comprises a housing 10 of insulating material and is formed in two parts for assembly purposes. Such housings are well-known in the art. Enclosed within the housing are two socket connectors 11 and 12, one of which, 11, is connected directly to a lead-in wire through metallic conducting strip 13, the 50 other 12 to the other lead-in wire through the

switch which incorporates the present invention.

In the illustrated embodiment, a switch block 14 is enclosed within the two parts of the housing. The switch block is formed 55 of insulating material, such as porcelain. A contact plate 15 is attached on one side of the block and has affixed thereto the socket connector, 12, which is in electrical engagement with the plate. On the opposite side of the block, another contact plate (not shown) is secured. To the second contact plate, the lead-in wire for socket 12 is connected through conducting strip, 16.

There is provided a contactor or make-and-break element for electrically connecting and disconnecting the contact plates. As here shown as an example, the contactor includes a pair of curved contact arms, 17, connected by a bridge, 18, which straddles the 60 block in a slot 19 thereof. When the contactor is in circuit-closing position, the arms 17 engage the contact plates and said plates are connected electrically through said arms and bridge. The contactor, as shown, is of unitary sheet-metal construction.

The invention includes means for so mounting the contactor as to give it a shifting or variable pivot during its movements into and out of circuit-closing position. In the embodiment here illustrated, the switch block is formed with recesses in the opposite sides thereof and for the accommodation of legs 20 which extend from the contact arms 17 of the contactor. The legs are adapted to 65 oscillate or swing back and forth in the recesses and carry the contact arms into and out of engagement with the contact plates.

Although capable of various constructions, as herein shown, each recess is designed with 70 oblique angularly disposed side walls 21, defining an angular space open at the wide end and with a notch 22, at the point of convergence of said walls. Each notch is of curved, substantially semi-circular formation and 75 opens into the angular space between the walls. The curved wall of the notch meets the angular side walls at sharp corners, 23, which, in fact, act as shoulders or pivots, 80 as presently described. The wall of the notch 85

95

100

and portions of the angularly disposed walls may be lined with thin sheet metal, 24, to provide a metallic bearing surface and eliminate wear on the material of the block.

- 5 The ends of the legs extend into the angular spaces of the recesses through the open ends thereof and have free bearings in the notches. The legs terminate in curved ends for sliding freely over the curved surfaces 10 of the notches. Although subject to modification in design, each of the leg ends is formed with relatively sharply curved bearing portions, one, 25, at the bottom end and one 26, 27 at each side, the sharply curved 15 portions being connected by relatively slightly curved portions. There is thus produced a substantially pear-shaped end on each leg. As the legs oscillate, one or the other of the bearing portions ride on the curved surfaces 20 of the notches. On one side of each leg, there is a straight edge, 28, which abuts and contacts with a side wall, 21, in one extreme position of the leg. Another straight edge, 29, is provided on the opposite side of each leg 25 for engagement with the other side wall, 21, in the other extreme position of the leg. The extreme positions of the legs are thus defined and limited by the angularly disposed side walls of the recesses.
- 30 Means are provided for actuating the contactor to move it into and out of circuit closing position. In the example herein disclosed, the actuating means include a coil spring, 30, which extends through the switch 35 block and has one end attached centrally to the bridge, 18. The other end of the spring is connected to a movable actuating member. The actuating member is exemplified as a slide, 31, which is arranged transversely in 40 the block opposite the contactor and is adapted for rectilinear movement in a slot of the block. The slide and contactor are pulled toward each other by the spring with the result that the slide is firmly held in its slot 45 and the leg ends of the contactor forced into the curved notches. The spring end is attached to the slide, substantially below the notches, and, to this end, a hook, lug or other catch, 33, may be provided on the shell for 50 the engagement of the spring end. The opposite ends of the slide project through and from the housing and are equipped with buttons, 34, 35.

The switch is operated by moving the slide back and forth by pressure applied to buttons, 34, 35. The movement of the slide carries the spring end secured thereto with it, changes the axis of the spring, and, consequently the line of force or pull of the spring. With the contactor in open circuit position shown in Figure 1, the line of pull of the spring is to the right of the pivot of the contactor and the contactor is held firmly against the right-hand wall, 21. When the slide is moved to the left by pressure applied to button 34, the

spring end attached to it is carried with it, the line of pull of the spring is changed, and travels past the pivot of the contactor. The spring then exerts its pull on the left hand side of the pivot and causes the contactor to snap over until limited by left-hand wall, 21. The circuit is now closed by the contact arms, 17, engaging the contact plates on the switch block and completing the circuit between the plates through the contactor. The circuit is again broken by applying pressure to the other button, 35, and moving the slide to the right, thereby causing the line of force of the spring to move to the right of the pivot of the contactor and the contactor to snap back into its open circuit position against right-hand wall, 21.

The pivot of the contactor shifts during movement. In the circuit closing position, as shown by Figure 6, the edges, 29, of the legs of the contactor engage the left-hand walls, 21, of the recesses and the pear-shaped ends bear against the right side of the notches. Upon movement of the slide to the right, the contactor first pivots around the left corners, 28, and the pear-shaped ends slide down the notches, 22. When the legs are lifted off said corners (Figure 7), the pivot is changed to the pear-shaped ends, and points of contact of said ends,—the bottom and left said curved portions, 25, and 26,—with the walls of the notches. These points of contact slide smoothly on the walls of the notches. The result is a speedy movement of the contactor occurring just as the circuit is broken as well as a rolling or eccentric movement which persists until the edges, 28, of the contactor strike the right-hand corners, 23, and the contactor rocks into the open circuit position. (Figure 9.) The contactor has essentially an initial pivotal movement on corners, 23, and a subsequent rolling or eccentric movement as the pear-shaped ends act as the pivots, on the curved walls of the notches. The reverse of these movements occur as the contactor moves to circuit-closing position.

The speedy movement of the contactor just as it makes or breaks the circuit is very effective in reducing and breaking arcs that tend to occur. The eccentric movement of the contactor eases the tension and reduces the strain on the spring, prolonging the life of the spring and allowing the use of a stiffer spring than in the ordinary snap switch. The shifting variable pivot has the further advantage in that the contactor is thrown on or off with a shorter movement of the slide and with less effort.

In the modification shown in Figures 2, 3, and 4, the switch is positioned in an insulating casing, 40, and acts to connect or disconnect conductors, 41. The actuator embodies a slide, 42, having a lug, 33, for engaging the end of the spring. The slide is positioned within the casing and is manipulated from

outside the casing. To this end, a slide button, 44, may be located on the exterior of the casing and provided with a boss, 45, extending through a slot, 46, into the interior. Provision is made for detachably securing the boss to slide, 42. For this purpose, a screw, 47, having a thin elongated head, 48, may be threaded into the boss, 45. The head is passed through a narrow elongated slot, 49, in slide 42, and then given a turn, as in Figure 4, to prevent its withdrawal. This provides a firm, yet detachable connection of button, 44, to slide, 42.

What is claimed is:

1. An electric switch comprising means forming a recess having an angular space defined by angularly disposed side walls and a curved notch at the convergence of the walls freely communicating with the angular space and forming sharp corners at the connections with said walls, a contactor including a leg terminating in a substantially pear-shaped free end extending into said notch, said leg having straight edges for abutment with the side walls in extreme positions of the contactor, an actuator, resilient means associated with the contactor and operated by the actuator to impart snap movements to the contactor, and a contact engaged or disengaged by the contactor.

2. An electric switch comprising a member having a curved, substantially semi-circular notch terminating in sharp corners, a contactor including a leg having an end seating in said notch, means to maintain the leg end in said notch and to impart to the contactor swinging snap movements, the leg pivoting on the sharp corners during portions of the movements and rolling on the curved surface of the notch during other portions of the movements and a contact engaged or disengaged by the contactor.

In testimony whereof I have hereunto set my hand.

45 FREDERICK E. CARLSON.
